UNITED STATES PATENT OFFICE.

GEORGE EAGAR, OF DUNBOYNE, ONTARIO, CANADA.

GAS-SAVER.

1,339,441.

Specification of Letters Patent. Patented May 11, 1920.

Application filed March 26, 1919. Serial No. 285,398.

To all whom it may concern:

Be it known that I, GEORGE EAGAR, a subject of the King of Great Britain, and a resident of Dunboyne, in the county of 5 Elgin, in the Province of Ontario, Canada, have invented a new and useful Gas-Saver, of which the following is a specification.

This invention relates to gas savers and has particular relation to an apparatus or 10 appliance adapted to be used in connection with explosive motors employing gasoline or other highly volatile fuel.

The primary object of the invention is to provide means for saving and utilizing the 15 vapors which are given off by gasoline and the like by inducting them to the explosive chamber of the engine along with the explosive charge.

A practical embodiment of the invention 20 is shown in the accompanying drawings, and will be hereinafter described in detail, it being understood, however, that I do not limit myself to the specific embodiment of the invention herein shown, as various 25 changes may be made in practising the invention, without departing from the spirit or principle of same as herein shown and claimed.

In the accompanying drawings,

30 Figure 1 is a view in side elevation of an internal combustion engine showing one form of application of my device thereto,

Fig. 2, is a view in section of the controlling valve for admitting the gasoline vapor 35 to the manifold of the engine, and also showing in side elevation, partly broken away, the operating rod of the valve,

Fig. 3 is a horizontal sectional view taken on the line III—III of Fig. 2.

40 Fig. 4 is a sectional view of the vapor tube showing its attachment to the top of a gasoline tank, and

Fig. 5 is a top plan view of the same.

To put my invention into practice, for 45 instance, in connection with an internal combustion engine, I tap a nipple or short pipe as 10, into the manifold 11, of the engine, and connect the threaded neck 12 of a valve body 14 with this nipple or pipe 10. Obviously, 50 the neck 12 can be attached directly into the manifold, but as this neck in the ordinary valve is usually short, it is preferable to provide the nipple 10, in order to space the valve sufficiently far away from the manifold to permit free operation of an operating mechanism. Into the neck 15 on the

opposite side of the valve body, I thread a short pipe 16 both ends of which are open, and which pipe intermediate its ends is provided with a branch 17 extending at right angles to the pipe 16. The valve body 14 is provided with an ordinary plug valve 18, the port 19 of which is brought into or out of registry with the passageway through the valve body by a suitable operating means. 60 65

Where the device is used with the engine of an automobile, it is desirable, of course, that the valve may be operated by the driver from a point convenient to his seat. A convenient and thoroughly practical means for 70 so operating the valve is herein shown, and consists of a disk as 20, securely fixed on the stem 21, of the plug 18, and which disk is provided with a pair of openings as 21, which receive the forked ends or arms 22, 75 of an operating rod 23 extending through the dash board of the automobile where it may be conveniently reached by the operator.

It is well known, that a considerable 80 amount of vapor accumulates in the top of any tank of gasoline or other highly explosive oils, and this vapor is ordinarily permitted to escape to the atmosphere. It is my purpose to conserve this vapor and utilize 85 the power units that the same may contain in the explosive charge. To this end, I provide the gasoline tank as 24, with an opening as 25, and over this opening 25 I affix securely to the tank, a plate 26 which is provided with an upwardly extending tube 27, the bore of the tube being restricted or of such size as to provide a relatively small opening leading to the opening 25. Affixed 90 to the plate 26 surrounding the tube 27 is the 95 leg 28 of an elbow-shaped pipe, to the other leg 29 of which is connected one end of a tube 30; the other end of this tube is connected to the branch 17 of the pipe 16. The outer end of the leg 28 is open as at 31, 100 permitting the accumulating vapors to escape during the time the engine is standing idle.

The operation of the device will be at once apparent from the drawings taken with the foregoing description, as it will be observed 105 that with the engine in operation, with the valve 18 open, a suction will be created through the valve passageway and pipe 16, and through the flexible tube 30 and tube 27, this sucking the vaporized gasoline 110 from the top of the gasoline tank and making use of the same to assist in the running

of the engine in place of having this vaporized gasoline passing out to the atmosphere and being wasted.

Various changes may be made in the details of construction, as may be necessitated by conditions existing where the device is to be installed, without departing from the general spirit of the invention.

Having fully described my invention, 10 what I claim is:

1. In combination with a gasoline tank having a vent opening, and the manifold of an internal combustion engine, a valve body secured to the manifold and having its passageway communicating with the manifold, a valve in said body, operating means for said valve, and connections between the vent opening of the gasoline tank and said valve body.
2. In combination with a gasoline tank provided with an outlet for vapors generated in said tank, of a tube connected to the outlet, and a valve connected with the tube, and also connected with the manifold of an internal combustion engine, whereby the suction through the manifold will draw the vapors from the tank through the tube into the manifold of the engine.
3. In combination, a tank having a vapor outlet in the top thereof, a tube connected to the outlet, a valve to which the other end of said tube is connected, said valve being in communication with the manifold of an internal combustion engine, and means for opening and closing said valve.
4. The combination with the intake manifold of a gas engine, and fuel supply tank

having a vent opening, of manually controlled means for forming communication between the manifold and vent opening.

5. The combination with the intake manifold of a gas engine and a fuel supply tank provided with a vent opening, of means for forming communication between the vent opening and manifold.

6. In combination, a gas engine manifold, a fuel supply tank having an opening therein, a vent tube associated with said opening, an elbow inclosing said tube and having an opening to the atmosphere, and pipe connections between said elbow and manifold.

7. In combination, a gas engine manifold, a fuel supply tank having an opening therein, a vent tube associated with said opening, a valve-controlled pipe section connected to said manifold, and means for forming communication between said vent tube and pipe section.

8. In combination, a gas engine manifold, a fuel supply tank having an opening therein, a vent tube associated with said opening, an elbow inclosing said vent tube and having an opening therein at the angle of the elbow with the outer end of the vent tube in line therewith and means for forming communication between the elbow and manifold.

In testimony whereof, I have signed in the presence of the two undersigned witnesses.

GEORGE EAGAR.
